GLUE DISPENSER

Walker A. Leonard, New York, N. Y.

Application January 24, 1950, Serial No. 140,283

5 Claims. (Cl. 144—280)

1

This invention relates to glue dispensers, and more particularly to a dispenser for applying glue or other plastic adhesive under pressure into grooves in members such as wooden furniture parts.

It is among the objects of the invention to provide a readily portable glue dispenser of small size so that it can be conveniently carried and operated by one man but which, at the same time, has a large glue capacity and is effective to spread glue in thin layers or spots under pressure, which is simple and durable in construction and economical to manufacture, which effectively prevents spilling or smearing of the glue and depositing glue on the hands and clothing of the workman, and is light in weight, easy to use, and highly effective in obtaining a complete and even distribution of the glue on the contacting surfaces of parts to be glued together.

Other objects and advantages will become apparent from a consideration of the following description and the appended claims in conjunction with the accompanying drawings, wherein:

Figure 1 is a side elevation of a glue dispenser illustrative of the invention, portions being broken away and shown in cross section to better illustrate the construction thereof;

Figure 2 is an end elevation of the dispenser illustrated in Figure 1;

Figure 3 is a cross section on an enlarged scale of a fragmentary portion of the apparatus and is taken substantially on the line 3—3 of Figure 2;

Figure 4 is a transverse cross section on the line 4—4 of Figure 3;

Figure 5 is a longitudinal cross section on the line 5—5 of Figure 2; and

Figure 6 is a transverse cross section on the line 6—6 of Figure 5.

With continued reference to the drawings, the glue dispenser therein illustrated comprises, in general, a manually operated pump 10, a container 11 mounted on the pump and providing a glue reservoir, an applicator 12, a tubular conduit 13 connecting the applicator to the pump 10, and an actuator 14 connecting the pump operator to the outlet control valves of the applicator.

The pump 10 comprises a metal cylinder 15 having one end closed by an end wall 16 and its opposite end closed by a removable end wall 17 which has an internally screw threaded marginal flange threaded onto the externally screw threaded end of the cylinder. A handle 18 is secured at one end to the removable end wall 17 and has a pistol grip formation 19 extending

2

therefrom, and a trigger guard formation 20 adjacent the grip formation 19. A bore 21 extends through the handle 18 with its center line substantially in alignment with the longitudinal center line of the cylinder 15, and the end wall 17 is provided with an aperture centered on the center line of the bore 21. A piston 22 is reciprocable in the cylinder 15 and may comprise a disc of flexible material, such as soft rubber, compressed between two washers disposed at respectively opposite sides thereof. A piston rod 23 is secured at one end to the piston 22 and extends through the aperture in the end wall 17 and into the bore 21 in the handle. An opening 24 extends from the inside of the trigger guard 20 into the bore 21, and a lever 25, simulating a trigger, is pivotally mounted intermediate its length in the opening 24 and extends into the bore 21 where it is pivotally connected to the piston rod 23 near the adjacent end of the latter. Another portion of the lever 25 extends into the trigger guard and when this portion is pulled toward the grip formation 19, the piston 22 is forced toward the end wall 16 of the cylinder.

An aperture 26 is provided in the bottom wall of the container 11, and a registering aperture 27 is provided in the wall of the cylinder 15 intermediate the length of the cylinder, and the cylinder wall is provided intermediate its thickness with a slideway 28 which intersects the aperture 27.

A slide valve 29 is slidably mounted in the slideway 28 and is movable between a valve-closing position in which it intercepts the aperture 27 and closes off the interior of the container 11 from the interior of the pump cylinder 15, and a position in which it is clear of the aperture 27 so that the reservoir in the container 11 communicates with the interior of the pump cylinder.

An operating arm 30 extends perpendicularly from one end of the slide valve 29 inwardly of the cylinder, and has at its distal end an eye through which the piston rod 23 extends. A compression spring 31 surrounds the piston rod 23 between the piston 22 and the arm 30, and a compression spring 32, stronger than the spring 31, surrounds the piston rod in the bore 21 between the piston end wall 17 and an abutment washer 33 secured on the piston rod.

The spring 32 moves the piston 22 to a location adjacent the end wall 17, compressing the spring 31 and moving the slide valve 29 to a position in which the registering apertures 26 and 27 are both open and the interior of the container 11 communicates with the interior of the cylinder

15, so that glue in the container will flow into the cylinder. If the lever 25 is now manually operated to force the piston 22 toward the opposite end wall 16 of the cylinder, the spring 31 will first lose its compression and will then exert a tension force between the piston 22 and the slide valve arm 30, this spring being connected at its respectively opposite ends to the piston and to the slide valve arm, and will move the slide valve to a position in which it closes off the aperture 27 before the piston 22 reaches the end wall 16. This closing of the aperture 27 will prevent return flow of glue from the cylinder back into the container 11, and the glue in the cylinder will then be forced by the piston through the tubular fitting 34 into the conduit 13 which is threaded at one end into the fitting 34, and through the conduit into the applicator 12.

A push rod 35 is slidably mounted in the handle bore 21 outwardly of the piston rod 23, and has on its outer end a knob or saddle 36 by means of which pressure can be applied to the push rod by the thumb or palm of the hand of the workman using the glue dispenser. The push rod 35 is urged outwardly of the handle by a compression spring 37 which surrounds the push rod in the bore 21 between an abutment 38 fixed in the bore, and a washer 39 secured on the push rod. Outward movement of the push rod is limited by an abutment 40 at the outer end of the bore 21 which abutment is apertured for the passage of the push rod 35 therethrough.

The piston rod 23 and the push rod 35 have head formations on their adjacent ends and, when the force exerted on the lever 25 is not sufficient to force the glue from the pump cylinder into the applicator 12, additional pressure may be exerted on the glue by manually pushing the knob or saddle 36 inwardly of the handle.

The container 11 may conveniently comprise a hollow can of cylindrical or other desired shape, having one open end and having at its other end a bottom wall 41 secured to the wall of the cylinder 15 by suitable means, such as the cap screws 46 extended through apertures in the outwardly flanged, upper portion of the cylinder wall 15 and threaded into screw-threaded recesses in the bottom wall 41 of the container, as particularly illustrated in Figure 4.

A flanged cover 42 fits onto the open end of the container 11 and is provided with a handle 43 in the form of a staple for facilitating removal of the cover from the container. The container has, on one side, a handle 44 in the shape of a downwardly directed hook, and has at its opposite side a generally C-shaped handle 45 which extends outwardly from the side of the container and serves as a prop for supporting the container when the device is laid on its side.

The applicator 12 is a thin walled, hollow box of elongated rectangular shape having a width slightly less than the width of the groove into which the glue is to be applied so that the applicator will slide freely in the groove. Where the work involves the application of glue into grooves of different widths, a set of applicators of different widths may be provided and may be selectively connected to the tube or spout 13 to accommodate the dispenser to the particular job.

In the arrangement illustrated the applicator has spaced apart, substantially parallel side walls 47 and 48, end walls 49 and 50, and a bottom wall 51. The bottom wall is provided with two generally rectangular openings 52 and 53 which constitute outlet or dispensing openings for the ap-

plicator through which the glue flows from the interior of the applicator to the work surface to which it is applied. The dispensing of glue through these openings is controlled by a valve mechanism operated by the trigger lever 25 of the pump. This valve mechanism comprises two rectangular slide plates 54 and 55 slidably mounted on the inner surface of the bottom wall 51 of the applicator in position to respectively overlie the openings 52 and 53. A shaft 56 is journaled at its lower end in a socket provided on the inner side of the bottom wall 51 substantially at the center of the bottom wall area, and this shaft extends from the bottom wall through the top cover 57 of the applicator and is journaled in the cover. A bar 58 is secured at its mid-length location to the shaft 56 near the bottom wall 51 of the applicator, and links 59 and 60 connect the respectively opposite ends of the bar 58 to the slide plates 54 and 55 so that when the shaft is rotated in one direction, the slide plates will be moved toward each other and will uncover the openings 52 and 53, and when the shaft is rotated in the opposite direction, the plates will be moved away from each other and toward the corresponding ends of the applicator to cover the openings 52 and 53 and preclude further flow of glue through these openings. A radially projecting arm or crank 61 is secured at one end to the shaft 56 above or at the outer side of the cover 57, and the end of the actuator 14 opposite the end connected to the trigger lever 25 is connected to this crank 61.

The actuator 14 is preferably a Bowden wire or cable having a flexible outer casing 62, one end of which is secured to the cover 57 by a clamp 63, and the other end of which is secured to the trigger guard 20 by the clamp nuts 64. The wire or core 65 is slidable in the casing 62 and is secured at one end to the outer end of the crank 61, and is secured at its opposite end to the trigger lever 25 at the end of this lever opposite the end engaging the piston rod 23. The wire 65 is secured to the trigger lever by an adjustable connection including a nut 66 threaded onto an enlarged screw-threaded end portion of the wire.

This Bowden cable is extended through two staples or eyes 67 and 68 which project outwardly from the side of the cylinder 15 opposite the container 11 and at respectively opposite ends of the cylinder.

With this arrangement, when the trigger lever 25 is pulled toward the grip 19 to close the valve 29 and move the piston 22 toward the end wall 16 of the cylinder, thereby forcing glue from the cylinder through the spout or conduit 13 into the applicator, the actuator 14 simultaneously rotates the shaft 56 and moves the slide plates 54 and 55 in a direction to open the holes 52 and 53 in the bottom wall of the applicator so that the glue forced into the applicator by the piston 22 will flow through these holes onto the surface of the work piece. As soon as the trigger lever 25 is released, the spring 32 will retract the piston 22 in the cylinder 15 and will simultaneously move the trigger lever so that the portion of this lever within the trigger guard 20 is moved away from the grip 19. This movement of the trigger lever acting through the Bowden wire actuator 14 will rotate the shaft 56 in a direction to move the slide plates 54 and 55 back over the holes 52 and 53, thereby terminating any further dispensing of glue from the applicator.

The cover 57 is a flat body having a marginal flange 69 which receives the applicator box at

the open end of this box opposite the bottom wall 51, and the cover is secured to the box either frictionally or by suitable fasteners, such as screws or pins.

A boss or fitting 10 on the cover 57 receives the corresponding end of the conduit or spout 13, and this conduit is sufficiently rigid so that the applicator can be slid along a groove in a work piece by manual force applied to the grip 19 of the dispenser.

Since at times it may be desired to use the applicator for spot gluing, means are provided for closing off one of the holes in the bottom wall of the applicator to condition the dispenser for this type of operation.

In the arrangement illustrated, this means comprises a boss or stem 71 extending perpendicularly from the inner side of the cover 57 into the applicator above the opening 53 and having a bore therethrough, and a counterbore in its end remote from the cover. A stem 72 extends through the boss 71 and through an aperture in the wall of the cover and carries, on its lower end, a plate 73 of a size and shape to cover the opening 53 when the slide plate 55 is withdrawn from this opening. A spring 74 surrounds the stem 72 within the counterbore in the boss 71, and bears at one end against the end wall of the counterbore, and at its opposite end against an abutment washer 75 secured on the stem to resiliently raise the plate 73 to a position, as illustrated in Figure 1, in which it is clear of the slide plate 55. A knob 76 is secured on the end of the stem 72 opposite the end to which the plate 73 is secured, and at the outer side of the cover 57, and a pin 77 extends through the stem between the knob 76 and the cover 57. A latch 78 is secured to the cover and is engageable by the pin 77 to hold the stem 72 inwardly against the force of spring 74 with the plate 73 covering the opening 53. When the opening 53 is thus covered, only the opening 52 will be open and this opening 52 may then be used for applying glue spots to a work surface at such locations as may be desired. In order to use the applicator for spot gluing with the opening 53 covered by the plate 73 wire 65 is disconnected from shaft 56 so that the trigger 25 can be used to expel the glue without moving the slide plates 54 and 55. Shaft 56 is turned to a position such that the slide plates are moved inwardly and hole 52 is left open.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A glue dispenser comprising a hand operated pump, a container mounted on said pump and providing a glue reservoir communicating with the interior of said pump, a glue applicator, a tubular conduit connecting said applicator to said pump, first valve means between said container and said pump, second valve means in said applicator controlling the outlet thereof, and means connecting said pump to said first and second valve means and operative to close said first valve means and open said second valve

means when said pump is operated to force glue from said container to said applicator.

5 2. A glue dispenser comprising a pump including a cylinder, a handle secured to one end of said cylinder, a piston reciprocable in said cylinder, a piston rod extending from said piston through said one end of said cylinder into said handle, a manually operated lever mounted on said handle and engaging said piston rod to force 10 said piston toward the other end of said cylinder, spring means engaging said piston rod and resiliently urging said piston toward said one end of said cylinder, a spout extending from said other end of said cylinder, an applicator on the 15 end of said spout remote from said cylinder, a container mounted at one end on said cylinder, said container and said cylinder having registering apertures providing communication between the interior of said container and the interior of said cylinder, a valve slidably carried by said cylinder and movable between a position in which it intercepts said apertures and a position in which it is clear of said apertures, and resilient means connecting said valve to said piston rod for movement of said valve to its aperture intercepting position when said piston is moved toward said other end of said cylinder.

20 3. A glue dispenser comprising a pump including a cylinder, a handle secured to one end of said cylinder, a piston reciprocable in said cylinder, a piston rod extending from said piston through said one end of said cylinder into said handle, a manually operated lever mounted on said handle and engaging said piston rod to 25 force said piston toward the other end of said cylinder, spring means engaging said piston rod and resiliently urging said piston toward said one end of said cylinder, a spout extending from said other end of said cylinder, an applicator on the 30 end of said spout remote from said cylinder, a container mounted at one end of said cylinder, said container and said cylinder having registering apertures providing communication between the interior of said container and the interior of said cylinder, a valve slidably carried by said cylinder and movable between a position in which it intercepts said apertures and a position in which it is clear of said apertures, resilient means connecting said valve to said piston rod for movement of said valve to its aperture intercepting position when said piston is moved toward said other end of said cylinder, said applicator having a bottom wall provided with a dispensing opening, valve means in said applicator 35 movable to open and close said dispensing opening, and actuator means connecting said valve means to said manually operated lever for moving said valve means to open said dispensing opening when said piston is moved toward said opposite end of said cylinder and to close said dispensing opening when said piston is spring retracted toward said one end of said cylinder.

40 4. A dispenser comprising a manually operated pump including a cylinder and a piston reciprocable in said cylinder, a container mounted on said cylinder and communicating interiorly with the interior of said cylinder, an applicator comprising a hollow structure having a bottom wall provided with a dispensing opening, a conduit connecting said cylinder to said applicator for the transmission of material from said container to said applicator upon operation of said pump, valve means between said cylinder and said container, means including a spring connecting said valve means to said piston for operating

ation of said valve means coincidentally with said piston to close off said container from said cylinder when said pump is operated to force material from said cylinder through said conduit to said applicator, valve means in said applicator for opening and closing said dispensing opening, and means connecting said last-mentioned valve means to said pump to open said dispensing opening when said pump is operated to force material from said cylinder to said applicator.

5. A dispenser comprising a manually operated pump including a cylinder and a piston reciprocal in said cylinder, a container mounted on said cylinder and communicating interiorly with the interior of said cylinder, an applicator comprising a hollow structure having a bottom wall provided with two spaced apart dispensing openings, a conduit connecting said cylinder to said applicator for the transmission of material from said container to said applicator upon operation of said pump, valve means between said cylinder and said container operated coincidentally with said piston to close off said container

10

from said cylinder when said pump is operated to force material from said cylinder through said conduit to said applicator, valve means in said applicator for opening and closing said dispensing openings, means connecting said last-mentioned valve means to said pump to open said dispensing openings when said pump is operated to force material from said cylinder to said applicator, and manually operated means carried by said applicator for maintaining one of said dispensing openings closed when said openings are opened by said last-mentioned valve means.
